UNITED STATES PATENT OFFICE.

CHARLES E. WEISGARVER AND JOHN D. HARNISH, OF HARRISBURG, PENNSYLVANIA.

FLOAT-OPERATED CIRCUIT CLOSER.

Application filed December 30, 1922. Serial No. 609,964.

This invention relates to control devices which are operated hydroelectrically in combination with a mercury column and other elements which operate to open and close an electric circuit, and the primary object of this invention is to provide means for controlling the action of hydraulic pumps such that a certain predetermined head may be maintained in reservoirs or similar devices wherein is stored a quantity of liquid to be drawn off according to the requirements of the installation.

Another object of this invention is to provide means for hydro-electrically controlling the pump action such that a predetermined pressure head is maintained against which the pumps operate, such action being entirely automatic thus eliminating the personal element and thereby reducing the cost of the operation.

Another object of this invention is to provide a plurality of mercury containers, one of which is in piped relation with the pressure head, while another is in piped relation with the first and positioned above the first at such height that the weight of a column of mercury between the containers will balance the pressure head that is desired to be maintained in the reservoirs or other containers.

A further object of this invention is to provide a rugged trustworthy device of the character described, that will operate within defined limits at all times with a minimum amount of attention and maintenance cost.

With these and many other objects in view which will be more readily apparent as the nature of the invention is better understood, the same consists in the novel construction, combination, and arrangement of parts as will be hereinafter fully pointed out illustrated and claimed.

It will be quite readily understood by those skilled in the art to which this invention belongs that the same is susceptible to various changes and modifications without departing from the spirit or scope of the invention, but a preferred and practical embodiment of the invention is shown in the accompanying drawings in which;

Figure 1 is an elevational view showing the mercury containers positioned one above the other, the lower one being adapted to be

connected to the pressure head while the upper one is in piped relation with the lower container.

Figure 2 is a side elevation of the parts shown in Figure 1 of the drawings.

Figure 3 is a diagrammatic view showing the method of connecting the pressure head with the mercury containers.

Figure 4 is a side elevational view of the circuit closing and opening device positioned above the upper mercury container shown in Figure 1.

Figure 5 is a plan view of the parts shown in Figure 4 of the drawings.

Figure 6 is an end view of the parts shown in Figure 4 of the drawings.

Similar reference numerals refer to similar parts throughout the several figures of the drawings.

In carrying out the application of this invention to an hydraulic pumping system I provide a motor driven pump designated in its entirety by the numeral 10. The pump 10 is provided with a suction pipe 11 and a discharge pipe 12, the suction pipe being connected to the source of supply and delivery pipe 12 to the reservoir into which water is to be delivered.

In addition to suitable check valves being installed in the delivery pipe, there is provided a pipe connection 13, through which a quantity of liquid delivered by the pump 10 rises to a pressure tank 14, which is preferably located on a level with or slightly above the upper mercury container 15 for the purpose of preventing the mercury from being discharged into the tank when an unusual low reduction in head is made.

In installations where it is not possible to position the pressure tank 14 at a level approximately equal to or above the upper mercury container 15 (as shown in the drawings) it is desirable to run a pipe 16 above the mercury container 15 in order to form a liquid seal against the flow of mercury into the tank 14.

In installations where quick action valves are used the introduction of the pressure tank 14 prevents severe shocks to apparatus and acts as a shock absorber between the supply line 12 and the mercury container 15 and as a means of further minimizing the shocks a choke fitting 17 is installed in the pipe line 13 which connects the supply

line 12 to the pressure tank 14 as shown in Figure 3 of the drawings.

In addition to the mercury containers and the piping associated therewith, the control device consists of an electric switch designated in its entirety by the numeral 18, and consists essentially of a make and break contact system which is actuated through a float 19 positioned above the surface of the mercury in the container 15.

The float 19 is provided with a stem 20 to which is slidably secured a plurality of collars 21 and 22 each of which are made cone shaped, the cone engaging a switch operating dog or lever 23 on the underside 24 when the switch is opened and the cone on the collar 22 engaging the upper edge 25 of the lever 23 when the switch is closed. The lever 23 is fulcrumed on pin 26 which is positioned in a bracket 27, the base of which rests on a plate 28 that forms a top cover for the mercury container 15. The bracket 27 is preferably provided with two upstanding ears 29 and 30 through which the pin 26 is adapted to pass. The extended end of pin 26 forms the fulcrum for the lever 23 as shown in Figure 4 of the drawings.

The pin 26 also forms a fulcrum for an inverted U shaped floating lever 31, the trough of which is preferably fitted with a mass of metal represented in this particular installation by a block 32, and held therein by a rivet 33, or similar means. The primary object of this mass is to increase the moment of the lever 31, the utility of which will be explained later. The floating lever 31 is provided with a pin 34 which has an extension 35 positioned between the rivet 33 and the fulcrum pin 26. The pin 35 is adapted to be engaged by surfaces 36 and 37 cut in the lever 23. The floating lever 31 is further provided with pins 38 and 39 each of which is adapted to engage the surface 40 of a rocking lever 41 which is also fulcrumed on pin 26. The lever 41 is provided with a bent upward, backward and downward portion 42 which forms a rectangle adapted to be filled with lead or some other moment increasing mass.

The lever 41 is further provided with a circuit closing element 43, which is adapted to be rigidly secured to the lever 41 but insulated therefrom.

Referring to Figures 1 and 5 of the drawings it will be observed that terminal 44 which is connected to the power supply is out of contact with the terminal 45 which is connected to the motor that rotates the pump shown in Figure 3 in which case the motor is idle and the pumps have ceased to operate and the storage reservoir in this condition is filled while the operating elements

of the switch are positioned as shown in Figure 4 of the drawings.

As water is drawn from the reservoir the pressure in the pipe 12 is decreased and consequently the pressure in the tank 14 becomes less as the head is reduced and the pressure against the mercury column is reduced. The float 19 travels downward carrying the stem 20 together with the collars 21 and 22 with it. The collar 22 engages the surface 25 of the lever 23 as the mercury in the container 15 recedes, the stem 20 continues to travel down carrying the lever 23 with it and this action will continue until the floating lever 31 is raised to a vertical position and falls in the direction of the stem 20, at which time the pin 39 will strike the surface 40 of the lever 41 and the circuit closing element 43 will engage the terminal 44 with such force as to drive the blade portion down between the fingers 47 of the terminal 44, at which time the power current will pass through terminal 44 and out on the lead 45 to the motor thus completing the circuit to the motor at which time the motor will start and the pumps will operate until the pressure head in the reservoirs raise the mercury column until the collar 21 engages the surface 24 of the lever 23 and continues to move upward until the floating lever 31 again occupies the position shown in Figure 4 of the drawings at which time the circuit will be broken and the pumps will cease to operate.

Having thus described our invention what we claim and desire to be secured by Letters Patent is—

A float operated circuit closer adapted for use with a stem having spaced abutments thereon, comprising a supporting frame, an actuating lever pivoted to the frame and having one end located between said abutments, said lever also having a notch, another lever fulcrumed at one end and having a weight at its other end, a lateral projection carried by the weighted lever and adapted to be engaged by the side walls of the notch in the first actuating lever, a terminal carrying lever fulcrumed between its ends in the frame and having a terminal at one end and weighted at the other end, pins carried by the first named weighted lever and adapted to engage the terminal carrying lever on opposite sides of its fulcrum, said levers all having a common fulcruming axis, and a terminal element carried by said frame and located in the path of the terminal carrying lever.

In testimony whereof they affix their signatures.

CHARLES E. WEISGARVER,
JOHN D. HARNISH,
